(57) **CLAIM**

I claim the ornamental designs for trophy pedestals, as shown and described.

DESCRIPTION

FIG. 1 is a front/right/top perspective view of a trophy pedestal, for which a rear/left/top perspective view would be identical;

FIG. 2 is a front/right/bottom perspective view thereof, for which a rear/left/bottom perspective view would be a mirror image thereof;

FIG. 3 is a left side elevational view thereof, for which right side, front, and rear elevational views would be identical;

FIG. 4 is a top plan view thereof; and,

FIG. 5 is a bottom plan view thereof.

The broken lines immediately adjacent the shaded areas represent the bounds of the claim and all other broken lines showing the bottom of the trophy pedestal are for the purposes of illustrating environment. None of the broken lines form a part of the claimed design.
